UNITED STATES PATENT OFFICE.

JOHN HUGH O'NEILL, OF SPRINGFIELD, MISSOURI.

BOUNCING DOLL.

Original application filed October 28, 1922, Serial No. 597,601. Divided and this application filed August 1, 1924. Serial No. 729,532.

This application is divided out from my application Serial No. 597,601 filed Oct. 28, 1922.

The object of my invention is to provide sanitary, unbreakable and artistic dolls, marionettes and toys which are adapted to perform new uses as toys of very unusual qualities.

My improvements consist in combining a metal skeleton of coil springs with flesh material such as sponge rubber with or without a cover skin of flexible material such as rubber, and the methods of manufacturing the same.

The arms and legs of dolls and fore and hind legs of animal toys may have compressible and extensible springs as part of their metal anatomy, so that the dolls and animals will spring when dropped or when held down and then released. The head also may contain a compressible and extensible spring or there may be continuous compressible and extensible springs from head to feet, so that if the toy is dropped to the floor on its head or feet or on all fours it will bounce.

My invention is shown in several embodiments in the following description and appended drawings, in which:

Fig. 1 is a half mold with a section of a doll in place.

Fig. 2 is a partial section of a doll showing a dense rubber covering on the legs and feet.

Fig. 3 is a combined sheet of raw solid or dense rubber and raw sponge rubber.

Referring to the drawings; the compressible and extensible spring anatomy 1 may be of springs of uniform strength throughout, or may have stiffer parts between joints and more flexible parts at the joints and may be embedded in any position in any part of the body of a doll, marionette or toy in which the body is composed of flesh material of soft, flexible or elastic nature, preferably of molded sponge rubber 2, with the spots such as the feet 7 subjected to most wear preferably reinforced with solid or dense

rubber 3 and the whole covered by the skin formed in molding the sponge rubber, or a skin of solid rubber 4, as shown in Fig. 2, 50 or of any other flexible or elastic material. 5 is a half mold and is shown with the doll 6 in place. The ends of the compressible and extensible spring anatomy 1 may be fastened in the solid rubber wearing pieces 3 55 in the head and feet and the solid rubber be used to bounce the doll or toy on.

The solid rubber skin 4 may be placed raw in the mold and vulcanized to the sponge rubber 2 at one heat or may be of cured 60 rubber placed in the mold with the spring anatomy 1 and head and feet pieces of solid rubber 3 and raw sponge rubber material 2 inside the cured rubber skin 4. In this case the sponge rubber material 2 will expand 65 while vulcanizing and press the cured rubber skin 4 out against the surface of the mold and be vulcanized to the skin 4.

In Fig. 3 is illustrated a section of raw rubber sheet 8 formed of a layer of sponge 70 rubber mixture 2 and a layer of solid rubber mixture 4. This sheet 8 is placed in each half of the mold with the solid rubber side 4 against the mold 5 and is the preferred way to enclose the anatomy of the doll or toy in 75 the sponge rubber, the anatomy being held in the mold 5 in any of the ways shown in the original application.

I claim:

1. In a bouncing doll an anatomy composed of compressible and extensible springs and sponge rubber, said springs being embedded in said sponge rubber, the latter thereby securing the springs in position and adding to the resilience of the doll structure. 80 85

2. In a bouncing doll an anatomy composed of compressible and extensible springs and sponge rubber, said springs being embedded in said sponge rubber, the latter thereby securing the springs in position and adding 90 to the resilience of the doll structure, and said compressible and extensible springs being continuous from head to foot.

JOHN HUGH O'NEILL.
